UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR A SCROLL CLAMP FOR LIGHT-REFLECTING BOWLS.

46,473.

Specification for Design.

Patented Sept. 29, 1914.

Application filed July 18, 1914. Serial No. 851,826. Term of patent 3½ years.

To all whom it may concern:

Be it known that I, CHARLES E. JONES, a citizen of the United States, residing at Chicago, in the county of Cook and State of Illinois, have invented a new, original, and ornamental Design for a Scroll Clamp for Light-Reflecting Bowls, of which the following is a specification, reference being had to the accompanying drawing, forming a part thereof.

The figure is a perspective view of a scroll clamp for light reflecting bowls, showing my new design.

I claim:

The ornamental design for a scroll clamp for light reflecting bowls as shown.

CHARLES E. JONES.
